UNITED STATES PATENT OFFICE.

FRANK A. HOWARD, OF ELIZABETH, NEW JERSEY, AND DOUGLASS G. TOMKINS, OF NEW YORK, N. Y., ASSIGNORS TO STANDARD DEVELOPMENT COMPANY, A CORPORATION OF DELAWARE.

LIQUID-DISPENSING DEVICE.

Application filed April 25, 1924. Serial No. 708,954.

To all whom it may concern:

Be it known that we, FRANK A. HOWARD and DOUGLASS G. TOMKINS, citizens of the United States, residing, respectively, at Elizabeth, in the county of Union, State of New Jersey, and New York, in the county of Bronx, State of New York, have invented new and useful Improvements in Liquid-Dispensing Devices, of which the following is a specification.

This invention relates to liquid-dispensing devices, particularly those of a character suitable for facilitating supply of controlled amounts of oils, etc. The invention will be understood from the following description, taken in connection with the accompanying drawing, in which—

Fig. 1 is a longitudinal sectional view of one form of construction contemplated;

Fig. 2 is a bottom view of the device;

Figs. 3 and 4 are isometric views of details;

Fig. 5 is a longitudinal sectional view of a modification; and

Fig. 6 is a similar view of another modification.

In the drawing the reference character C designates a container, which may be made up of tin-plate or other suitable sheet material and which may vary somewhat in its precise form, but preferably will be of square or rectangular cross section, as more convenient for handling. Advantageously the container may be assembled of a body section 1, a top 2, a nozzle or spout 3 preferably of polygonal cross section, and a bottom 4. The spout 3 is provided with an inturned or inserted flange member 5 which is shaped to form a valve-seat 6 against which may rest a valve 7 having a washer of leather, prepared fiber or other desired material. The valve is carried on the end of the rod 8 which is compensating as to length, as by being provided with curvatures 9 or other means to allow of a small amount of longitudinal take-up for a purpose to be referred to more in detail hereinafter; and near the other end of the rod is secured a vent-valve 10, which advantageously may have a securing sleeve 11 extending to and embracing the rounded or enlarged end of the valve rod 8 and so as to project therewith through the vent opening in the bottom 4. The vent-valve 10, as in the case of the spout valve 7,

is provided with a suitable washer face to 55 coat with the valve seat 12. The bottom member 4 has a cam-like projecting surface or ridge 13 (which may be integral) against which a holding bar 14 rides. This bar is swiveled on the end of the valve rod 8, and while it may be so attached in several various manners, a convenient construction is that represented in Fig. 3 in which the bar is shaped up of sheet metal and closed in place with the recessed shoulders 15 embracing the enlarged end of the rod. Another convenient construction is that represented in Fig. 4 in which a section of a rod or tube 14' is centrally split and finally secured by being pressed up into engagement so as to 70 enclose the end of the rod.

With the bar 14 swung around on the cam ridge 13 into the diametrically-spaced depressions 16 the valve rod 8 is allowed to slack forwardly, and when inverted the spout valve 7 is unseated and the container can be filled on a suitable charging device. Similarly, in use, by inverting the container and swinging the bar 14 around into the depressions 16 the oil or other liquid can be 80 discharged to the amount desired and the valve 7 then be closed by swinging the bar 14 around back up on the cam ridge until tight. It will be noticed that while the spout valve 7 is open the vent-valve 10 is 85 also unseated so as to allow access of air to permit flow; but when the spout valve is drawn up against its seat the vent valve 10 is also drawn up against its seat and the container can be set upright or be placed in 90 any position without danger of leakage at either bottom or spout. The compensating curvatures 9 in the rod 8 allow of sufficient take up either way to at all times insure the simultaneous seating of both valves.

In the form of construction shown in Fig. 5 the cam-ridge 13' is provided on an insert member 17 set in additionally to the bottom member 4', thus providing somewhat greater 95 durability.

In the form shown in Fig. 6 the valve 7 is arranged to be automatically held open or unseated while in the filling machine. For this purpose the valve is provided with a projection having a middle enlargement 18 and surfaces tapering therefrom fore and aft. Spring fingers, indicated in dotted lines at 19, are arranged in the socket of the filling 100 105

machine and as the can is being placed in filling position ride up the front tapering surface and snap over the enlargement 18 and in the final position of the parts hold the valve out from its seat. On completion of the filling operation, by swinging the bar 14 around on the cam surface the valve rod 8' is retracted and the grip of the spring fingers 19 is overcome and the valve is re-seated. To allow some freedom of motion of the valve 7 when the valve-rod 8' is slackened forwardly, the valve may be slidably connected to the rod 8', as by an extension 20 having an elongated lateral projection 21 extending through the slot of the link 22 on the end of rod 8' and headed over to prevent disengagement. This gives the desired mobility, and when the valve-rod 8' is finally retracted the valve is also properly seated.

We claim:

1. In a liquid-dispensing device, the combination of a container having a spout provided with an internal valve-seat and a bottom provided with a vent-opening, a valve-seat internally of said vent-opening, a valve for coacting with said spout valve-seat, means on said spout-valve whereby the valve may be held unseated, a vent-valve for coacting with the vent valve-seat, a compensating valve-rod carrying both said valves and projecting through said vent-opening, an external cam-ridge on the bottom about said vent-opening and having diametrically spaced depressions, and a holding bar swivelly mounted on said valve-rod so as to ride with its inner face on said cam-ridge.
2. In a liquid-dispensing device, the combination of a container having a spout provided with an internal valve-seat and a bottom provided with a vent-opening, a valve-seat internally of said vent opening, a valve for coacting with said spout valve-seat, a vent-valve for coacting with the vent valve-seat, a compensating valve-rod carrying both of said valves and projecting through said vent-opening, an insert member on said bottom carrying an external cam-ridge having diametrically spaced depressions, and a holding bar swivelly mounted on said valve-rod so as to ride on said cam-ridge.
3. In a liquid-dispensing device, the combination of a container having a spout provided with an internal valve-seat and a bottom provided with a vent-opening, a valve-seat internally of said vent-opening, a valve

for coacting with said spout valve-seat, a vent valve for coacting with the vent valve seat, a compensating valve-rod carrying both of said valves and projecting through said vent-opening, an external cam-ridge on said bottom having diametrically spaced depressions, and a holding bar swivelly mounted on said valve rod so as to ride on said cam-ridge.

4. In a liquid-dispensing device, the combination of a container having a spout provided with an internal valve-seat and a bottom provided with a vent-opening, a valve-seat internally of said vent-opening, valves coacting respectively with said valve-seats, a compensating valve-rod carrying said valves and projecting through said vent-opening, a holding bar swivelly mounted on said valve-rod, and cam means for positioning said holding bar.

5. In a liquid-dispensing device, the combination of a container having a spout-valve and a bottom provided with a vent-opening, a valve-seat internally of said vent-opening, valves coacting respectively with said valve-seats, a compensating valve-rod carrying said valves and projecting through said vent-opening, and an adjustable holding bar mounted on said valve-rod.

6. In a liquid-dispensing device, the combination of a container having a spout-valve and a bottom vent-valve, a valve-rod carrying said valves, and a holding bar of sheet-metal shaped up about and swivelly mounted on said valve-rod.

7. In a liquid-dispensing device, the combination of a container having a spout-valve and an internally seating bottom vent-valve, a compensating valve-rod carrying said valves, and cam-means for adjusting the position of the valve rod.

8. In a liquid-dispensing device, the combination of a container having a spout-valve and an internally seating bottom vent-valve, a valve rod, and a sleeve extending from said vent-valve and embracing the end of said valve-rod.

9. In a liquid-dispensing device, the combination of a container having a spout-valve and an internally seating bottom vent-valve, and a valve-rod carrying said valves, said rod having curvatures to allow longitudinal compensation.

FRANK A. HOWARD.
DOUGLASS G. TOMKINS.
